[57] CLAIM

The ornamental design for seat, as shown and described.

DESCRIPTION

FIG. 1 is a perspective view taken from the top, front and right side of a seat embodying my new design in the form of a sofa;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left side elevational view being the mirror image of the right side shown; and,

FIG. 7 is a perspective view taken from the top, front and right side of an alternate embodiment of my invention in the form of a chair wherein the difference is substantially a matter of length.
